UNITED STATES PATENT OFFICE.

J ED SHERIFF, OF NEW YORK, N. Y., ASSIGNOR TO GEORGE A. SYKES, OF NEW YORK, N. Y.
VACUUM CONTAINER.

Application filed July 29, 1922, Serial No. 578,128. Renewed June 10, 1925.

To all whom it may concern:

Be it known that I, J Ed SHERIFF, a citizen of the United States, residing in New York, county and State of New York, have invented certain new and useful Improvements in Vacuum Containers, of which the following is a specification.

The present invention relates to an improved form of seal or closure for containers, whether of metal, glass or other material, whereby a lasting and reliable sealing may be effected. The invention is particularly useful in connection with vacuum jars, and especially where dry material, such as dehydrated foods, is to be preserved in vacuo.

It has been found by experiment that, in order to make rings of rubber and the like thoroughly and lastingly effective for sealing purposes, such rings should be subjected locally to a high compression on each unit of surface, and should be so mounted as to have room within which to move, to accommodate itself to the biting effect of such compression. Moreover, for securing the best results it is found advisable to combine the method above outlined with a telescoping friction fit, which may be utilized either with a layer of rubber (as is best with glass jars) or without this auxiliary.

Certain preferred forms of the improved seal are shown in the accompanying drawings wherein Figure 1 shows the various parts, in section and separated, as preferably employed for glass jars, figure 2 shows in perspective a portion of a modified form of rubber ring capable of use in connection with the apparatus shown in Figure 1, Figure 3 is a view similar to Figure 1, but showing the parts as located when the seal is completed, Figure 4 is a transverse section showing the modified form of seal as preferably used for thin-walled containers, as, for instance, tin cans, and Figure 5 is a partial section of another modified form for tin cans and the like.

The various forms of container shown in the drawing are all of that type in which the seal is effected by exhausting the container, and wherein the seal is preserved by the external atmospheric pressure. Various means are already known in this art for producing the vacuum for sealing jars of this kind.

In Figure 1, the upper portion of a glass

jar is shown at 10, the same having the usual reduced portion or neck 11 at the top. The interior of the neck 11 presents a smooth cylindrical wall 12 immediately surrounding the opening of the jar, and above this cylindrical inner wall the neck widens abruptly out to an annular exterior upstanding collar 13.

Between the wall 12 and the collar 13, and quite near the edge of the opening a circular biting ridge or bead 14 is located, and between this ridge and the outer collar 13, there is a curved depression running all around the neck of the jar.

The closing and sealing means comprise a resilient ring, preferably of rubber or rubber composition, and a removable cover adapted to fit the mouth of the jar in the manner shown in Figure 3. Inasmuch as it is found practically impossible to manufacture glass jars without inequalities and irregularities of curve, the sealing ring used is so made as to fit the cylindrical wall 12 as well as the upturned portion of the neck.

In the form shown in Figure 1, a molded rubber ring is used having a horizontal flange 15 and a vertical skirt 16, joined at right angles. The flange 15 fits over the upturned edge of the jar, while the skirt 16 fits snugly within the wall 12 (see Figure 3).

The cover is provided with a convex cylindrical depending portion 17, while above and outside of this cylinder, the cover is furnished with a circular ridge or bead 18 corresponding to the bead 14 on the jar. A curved depression running all around the cover separates the bead 18 from the cylindrical portion 17.

When the vacuum has been produced and the jar is closed, the parts assume approximately the position shown in Figure 3. Here it will be seen that the skirt 16 on the rubber ring fits between the cylinder 17 on the cover and the wall 12 on the jar. The horizontal part of the ring is firmly gripped between the horizontal portions of the cover and jar, in such a manner that the ridges or beads 14 and 18 exert a very high compression per unit of area upon the rubber. This causes the rubber to expand into the adjacent curved hollow portions of the cap and jar. The biting pressure exerted vertically is combined and cooperates with the tele-

scoping frictional engagement within the cylindrical wall 12, and a very effective seal is thus secured.

It is not essential that a molded rubber ring 15, 16, should be used. In Figure 2 is shown a substitute cut ring having two parts 19, 20 on each side of a circular bend. This may be used instead of the ring 15, 16, and the two parts 19, 20, will crowd into position 10 as shown in Figure 3, to form the vertical and horizontal portions of the ring respectively.

In Figure 4 is shown a thin walled container 21 preferably made of sheet metal. 15 The top of this container is slightly concave and the central opening is surrounded by a downwardly projecting cylinder 22, corresponding to the wall 12 in Figure 1. Surrounding the opening is a beading 23, 20 formed by an abrupt circular bend in the metal, and on each side of this beading the metal is preferably curved as shown to accommodate the rubber of the sealing ring. At some distance outside of this beading, a 25 circular ridge 24 is formed in the top which serves as a centering guide for the exhausting pump, the general position of which is indicated by the dotted lines in Figure 4.

The cap or cover is shown at 25. It is 30 provided with a deep peripheral cylinder 26 which tightly fits the cylinder 22, to form a telescoping friction seal, and the upper edge of this cylinder 26 is bent outward in a double curve to form a circular beading 27, 35 just outside of a circular curved depression which accommodates the compressed rubber.

In this modification the rubber ring used 40 may be a simple flat ring, as shown, since the telescopic friction fit can be obtained without the use of rubber. The beads 23 and 27 cooperate in compression of this ring 28 in the same manner as the beads 14 and 18 in Figure 2.

In Figure 5 is shown another form of cap 45 which may be used with sheet metal con-

tainers. Here the beading 27 is not produced by turning up the extreme outer edge of the sheet metal cap, but this outer edge is rolled instead, so as to present a rounded outer edge 29.

It is clear that this invention may be given a variety of embodiments without departing from its scope, and I do not limit myself to the details herein shown and described.

What I claim is—

1. A package comprising a container having an opening surrounded by a biting ridge, a cover fitting over said opening and provided with a biting ridge whose apex lies substantially vertically over the apex of the ridge on the container, and a sealing ring of yielding material adapted to come between said cover and container so as to receive the biting compression of the two opposed ridges.

2. An apparatus of the character described, a container having an opening and a neck surrounding the same provided on its upturned face with a biting ridge and an adjacent hollow extending around beside 70 said ridge; in combination with a cover having an under face provided with a biting ridge whose apex comes substantially directly over the apex of the ridge on the container and also having a hollow portion directly opposite the hollow on the container, and a sealing ring between said cover and container-neck adapted to receive the biting compression of said ridges.

3. A package comprising a container having an opening surrounded by a biting ridge, and a cover provided with a biting ridge on its under surface, said cover being so constructed as to center itself when applied to the container so as to bring its biting ridge substantially vertically over the ridge on the container.

In testimony whereof I have hereto set my hand this 27th day of July 1922.

J ED SHERIFF.
